(57) **CLAIM**

The ornamental design for a USB dongle, as shown and described.

DESCRIPTION

FIG. 1 is a perspective view of a USB dongle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an exploded perspective view, showing the USB dongle in an open configuration.

The dashed broken lines depict portions of the USB dongle that form no part of the claim.

1 Claim, 7 Drawing Sheets
